(57) **CLAIM**

The ornamental design for a marker device for use with a CNC layout table as shown and described.

DESCRIPTION

FIG. 1 is a perspective view of the marker device of this invention;

FIG. 2 is a top view of the marker device of this invention; FIG. 3 is a front side view of the marker device of this invention;

FIG. 4 is side view of the marker device of this invention; FIG. 5 is a rear view of the marker device of this invention; FIG. 6 is a second side view of the marker device of this invention; and

FIG. 7 is a bottom view of the marker device of this invention.
